UNITED STATES PATENT OFFICE

2,244,873

CONTAINER SEALER

John L. Ferguson, Joliet, Ill., assignor to J. L. Ferguson Company, Joliet, Ill., a corporation of Illinois

Application September 12, 1938, Serial No. 229,516

20 Claims. (Cl. 93—6)

This invention relates to container sealers and more particularly to a so-called universal container sealer in which containers of various sizes or dimensions may consecutively be sealed irrespective of their size within the limits of the machine, and without regard to the order in which they may be delivered to the machine.

Heretofore container sealers have been made which were adjustable to accommodate containers of any predetermined size within the limits of the adjusting mechanism. However, in such machines, it is necessary to manually adjust the machine or manually control the adjustment for each size of container which it is desired to seal. It is therefore an object of the present invention to provide a so-called universal sealer which requires no manual adjustment and is automatically adaptable to seal containers of any size or dimension within comparatively wide limits and irrespective of the consecutive order in which the various sizes of containers may be delivered to the machine.

A further object of the invention is to provide a comparatively small, compact universal sealer which may be operated at high speed for quantity production.

Another object is to provide a machine of the character described which is automatically adaptable to accommodate different sizes of containers and which will automatically apply adhesive and seal both ends of the containers.

A still further object is the provision of a completely automatic universal container sealer, wherein the adhesive applying means is adapted for the usual type of so-called skip gluing.

The device is adaptable for sealing various types of containers. However, the containers for which the present invention is particularly adaptable are usually comparatively large and are filled with relatively small cartons or cans or other objects with both ends of the containers unsealed. The upper flaps are normally vertically extended and the bottom flaps are closed so that the weight of the contents rests on the unsealed lower flaps. The containers are usually fed into the machine on a suitable conveyor forming a part thereof, whereby the lower flaps remain folded until a flap spreading device opens the lower side flaps at which time it is desirable to support the contents of the container with the lower end flaps closed while permitting the side flaps to be opened to a position in which adhesive may be applied. It is therefore an object of the present invention to provide a suitable feeding mechanism for various size containers by

which the bottoms of the containers may be retained in alignment in a horizontal plane during their passage through the machine, and the contents of the containers may be suitably supported while permitting the lower side flaps to be moved to adhesive applying position.

A further object is the provision of suitable means by which the containers may be separated and properly spaced and aligned during their movement through the machine in order that the succeeding containers may not interfere with the automatic adaptation of the various elements to the different sizes of containers.

Further objects will be apparent from the specification and the appended claims.

In the drawings:

Fig. 1 is a side elevation of one embodiment of the invention, the container receiving end of the machine being shown at the left of the drawings.

Fig. 2 is a top plan view of the embodiment illustrated in Fig. 1 with the conveyor guards or covers broken away for purposes of illustration.

Fig. 3 is a perspective view of the embodiment illustrated in Figs. 1 and 2 and taken from the receiving end of the machine.

Fig. 4 is a top view of a portion of the receiving end of the machine with the conveyor guards partly broken away, and illustrates particularly the container stop device for spacing the containers and the means by which the stop members are automatically synchronized with the movement of the conveyors.

Fig. 5 is a side perspective view of the feeding mechanism and stop mechanism illustrated in Fig. 4.

Fig. 6 is a perspective view of the sealer taken from the discharge end of the machine and particularly illustrates the driving mechanism and top flap closers.

Fig. 7 is an end elevation of the discharge end of the machine shown in Fig. 6.

Fig. 8 is a perspective view of the automatically adaptable adhesive applying mechanism.

Fig. 9 is a longitudinal sectional view through the adhesive applying mechanism and illustrates the method of operating the glue rolls, and the automatically movable carriage on which the upper glue rolls are mounted.

Fig. 10 is a fragmentary perspective view illustrating the angular feeder belts having a container thereon, and the support for the contents of the container and the end flaps thereof.

Fig. 11 is a diagrammatic view illustrating the stop means for the containers at the receiving

end of the machine whereby the containers are separated in a manner to be engaged by the conveyor flights and properly spaced for movement through the machine.

Fig. 12 is a somewhat diagrammatic top view of a machine equipped with a preferred form of container aligner whereby all of the containers irrespective of their width are aligned on the medial plane of the machine.

Fig. 13 is a side view of the aligner mechanism illustrated in Fig. 12.

Referring to the drawings in detail, the embodiment illustrated comprises a frame 1 supported on suitable legs as illustrated. The frame is provided with upwardly extending mechanism-supporting members 2, and these are connected at their upper ends by means of a longitudinal channel iron 3 as illustrated particularly in Figs. 1, 3, and 6. The uprights 2 may also support longitudinal guide members 4 which are mounted on each side of the machine and are arranged to support and guide longitudinally disposed endless conveyor chains 5 which are mounted on driving sprockets 6 adjacent the discharge end of the machine and on sprockets 7 adjacent the receiving end. The sprockets 7 are idlers and preferably are each mounted on an adjustable member 8 which may in turn be slidably supported on its respective guide members 4 and provided with an adjusting screw 9 whereby the conveyor chains may be suitably adjusted. The driving sprockets 6 at the discharge end of the machine are secured to vertical shafts 8^a and 9^a (Figs. 6 and 7) which are supported in suitable bearings on the frame. Suitable sheet metal conveyor guards or covers 5^a are mounted on the chain guides or otherwise supported over the conveyors.

The vertical conveyor shafts 8^a and 9^a are driven by means of a suitable motor 10 and a speed reducing mechanism 11 mounted on the frame 1. The speed reducing mechanism is provided with a transverse drive shaft 12 arranged to drive the vertical conveyor shafts 8^a and 9^a by means of beveled gears 13 and 14 respectively. The conveyor chains are provided with suitable spaced flights 15 by which the containers are carried through the machine with their rear walls in accurately spaced relationship. An adhesive applying mechanism is provided intermediate the ends of the machine for applying adhesive as the containers pass thereby. This mechanism will be described later.

At the receiving end of the machine spaced transverse shafts 16 and 17 (Figs. 1, 2 and 4) are mounted in suitable bearings and provided with pulleys 18 and 19 respectively for supporting a short belt-conveyor 20 on which the containers to be sealed may be delivered manually or by means of any suitable conveyor. The shaft 17 is driven from the speed reducing shaft 12 at the opposite end of the machine (Figs. 1 and 6) by means of a sprocket 21 on the speed reducing shaft, and a chain 22 driving a sprocket 23 secured to a transverse shaft 24. This transverse shaft 24 is provided with a suitable sprocket having a chain 25 thereon and arranged to drive a second transverse shaft 26 (Figs. 1 and 9) having a corresponding sprocket thereon. A chain 27 and suitable sprockets are arranged to drive another transverse shaft 28 from the shaft 26, and this shaft 28 is connected in driving relation to the belt-conveyor shaft 17 by means of a chain 29 on suitable sprockets. It will therefore be seen that the short receiving belt 20 may

be driven through the transmission just described and at a desired speed.

In the present invention the short conveyor belt 20 is preferably driven at a relatively low speed in order to permit a proper spacing of the containers as they enter the machine. The spacing mechanism and the means for supporting the contents of the containers with the end flaps closed, while permitting the side flaps to be opened to receive the adhesive will now be described.

Two angularly positioned spaced belts 30 (Figs. 3 and 4) are mounted on suitably angularly positioned pulleys 31 and on idler pulleys 32. These pulleys are mounted on a suitable frame 33 (Fig. 5) which is in turn supported upon the frame of the machine as shown. The pulleys 31 are preferably so-called stepped pulleys and the belts 30 are mounted on the large diameter step. The stepped pulleys 31 are driven from the shaft 28 by means of V-belts 34 mounted on the small diameter steps of the pulleys 31 and on appropriate pulleys on the shaft 28.

The angular belts 30 are preferably driven at a somewhat higher speed than the short conveyor belt 20 in order that the consecutive containers may be engaged by suitable stops and released thereby in timed relationship so that they are properly spaced and then moved through the machine by the conveyor flights 15.

The belts 30 are angularly positioned, as illustrated particularly in Fig. 10, so that, as the containers are moved forwardly into the machine, the lower side flaps 35 of a container 36 may drop downwardly thereon, as illustrated, and permit the container to pass onto a longitudinal supporting shelf 37 with the flaps 35 below the shelf and the closed end flaps and contents of the container resting on and supported by the shelf 37.

The front end of the shelf 37 is tapered substantially to a point, as shown, in order that it may easily enter between the bottom of the container and the flaps 35. The shelf extends from the receiving end of the machine to adjacent the discharge end, as shown in Figs. 3 and 6, in order that the contents of the containers may be suitably supported until the bottom side flaps are folded in a position to support the contents, after which the containers may be discharged from the machine. The shelf 37 may be mounted on brackets 38 (Fig. 9) which are in turn secured to a transverse plate 39 which is mounted on and may form a part of the frame 1. The brackets 38 are supported adjacent the median plane of the machine so that clearance is provided under the shelf 37 for movement of the container flaps.

As previously stated the angular conveyor belts 30 operate at a somewhat higher speed than the short conveyor belt 20 so that when a container moves onto the angular belts 30 the high speed of these belts causes each preceding container to be somewhat separated from the succeeding adjacent container and enables stop members to enter therebetween and momentarily stop the succeeding container to provide proper spacing. A container stop member is located on each side of the path of the containers and these members and the mechanisms for operation thereof, are identical on each side of the machine. Each stop mechanism is operated from its adjacent container conveyor and in synchronization with the movement of the flights thereon. It will therefore only be necessary to describe one

of these stops and the driving mechanism therefor.

Each of the stop members comprises a roller 40 normally positioned in the path of the containers and mounted on a bell crank lever 41 pivoted at 42 preferably on one of the conveyor guides 4. The lever 41 is provided with an arm 43 having a cam roller 44 thereon engaging a cam 45. A spring 46 retains the cam roller against the cam 45 and the movement of the cam is arranged to move the stops to release a container at the proper time and to engage a succeeding container. The cam 45 is secured to a short shaft rotatably mounted at 47 on the member 8 which supports the idler sprocket 7 on which the conveyor chain 5 is mounted. The cam is driven from the idler sprocket by means of a pinion 48 meshing with a gear 49 on the cam shaft 47. By this means the containers, irrespective of size, are properly spaced for delivery to the adhesive applying mechanism.

In order to properly align all of the containers, regardless of their width, on the vertical medial plane of the machine, resilient guide members are provided, one of which engages each side of the containers as they are moved along the shelf 37 and toward the adhesive applying device. These guide members comprise angularly positioned arms 50 pivoted at 51 and normally retained in the position illustrated in Fig. 4 by means of springs 52.

During the movement of the containers onto the pointed longitudinal shelf 37, the flaps 35 are partially open and these flaps are then completely opened during further movement by means of curved flap spreader rods 53 (Figs. 1, 3, 7, and 10) one end of which may be secured to the support 37 and the other end to any suitable part of the machine whereby the flaps may be completely opened to enable adhesive to be applied thereto. The flap spreaders 53 are arranged to completely open the lower flaps to a horizontal position and direct each flap between a lower roll 54 (Figs. 1 and 9) and a resilient presser member 55 whereby the glue roll will apply adhesive to the inner side of the lower flaps.

A glue roll is provided on each side of the machine and each roll is secured to a transverse shaft 56. An adhesive-containing glue box 57 is provided for each glue roll and the shaft 56 is rotatably mounted in suitable bearings on the glue boxes and each box is pivotally mounted on a transverse shaft 58 so that the boxes and glue rolls thereon may be raised to provide skip gluing. A cam 59 is secured to the glue roll shaft 56 and rests on a cam roller 60 mounted in any convenient manner on the transverse frame member 39. With each revolution of the glue rolls they are raised and lowered to provide the usual so-called skip gluing. The lower glue rolls 54 are continuously driven from the shaft 24 (Figs. 1 and 6) by means of a chain and sprocket connection comprising a chain 61 and a sprocket 62 secured to the glue roller shaft 56 and a suitable sprocket secured to shaft 24.

A gluing mechanism is also provided for the top flaps of the containers and comprises a vertically movable carriage 63 (Figs. 1, 8, and 9) on which the adhesive applying mechanism is mounted for vertical movement therewith. The carriage preferably comprises a U-shaped sheet metal member having side walls 64 and a flat bottom wall 65. A transverse plate 66 forms a portion of the bottom wall 65 and projects out-

wardly on each side of the carriage, as shown in Fig. 8, and flap supports 67 are secured to the outer ends thereof in spaced relation to provide flap guides to direct the upper flaps to the glue rollers. When the containers enter the machine the upper flaps are all extended substantially vertically, and suitable flap spreaders 68 are secured to the transverse member 66, or may be secured to the carriage side walls 64, for spreading the side flaps and directing them between the guide plates 66 and 67.

The carriage 63 is slightly narrower than the width of the narrowest container to be sealed and the front edges of the side walls 64 are curved as shown, and extend angularly upward so that as a container passes under the carriage these front edges will close the forward end flap. Substantially simultaneously with the closing of the front end flap, the rear end flap will be closed by a so-called flap tucker 69 which is pivoted on the carriage at 70.

The tucker 69 is provided with an arm 71 to which is connected a link 72, the opposite end of which is supported on a transverse shaft 73 by means of a slot 74 in the link. The shaft 73 is mounted in suitable bearings on brackets 75 secured to the longitudinal channel iron 3 forming a part of the frame of the machine. A cam roller 76 is mounted on the link 72 and engages a cam 77 secured to the shaft 73 whereby with each rotation of the cam 77 the tucker 69 will be operated to fold the rear end flap of a container. The tucker cam 77 is adjustably mounted on a sprocket 78 which latter in turn is secured to the shaft 73. The adjustment may be provided by means of bolt and slot connections as shown, whereby the tucker 69 may be suitably timed with the movement of the containers.

The sprocket 78 is continuously driven by means of a sprocket chain 79 which is in turn driven by means of a sprocket 80 (Fig. 6) secured to a transverse shaft 81 mounted in suitable bearings on the frame. A vertical extension 82 is provided on the vertical conveyor drive shaft 9 and the shaft 81 is driven therefrom by means of beveled gears 83.

Spaced guide brackets 84 (Fig. 9) are secured to each side of the channel iron frame member 3 for guiding the carriage 63 during its vertical movement, and rollers 85 are secured to each side of the carriage and engage the brackets 84. Thus the brackets provide a vertical track to enable vertical reciprocation of the carriage and to retain it in longitudinal alignment with the path of the containers. The rollers 85 are grooved to prevent lateral movement of the carriage. The carriage 63 is raised and lowered for each container which passes through the machine and the raising and lowering of the carriage is so timed with respect to the movement of the containers that during the downward movement of the carriage the curved front edge 64—a of the side walls of the carriage will engage on the top of the front wall of each container irrespective of the dimensions of the container and the engagement will always be at a point which will support the carriage and enable the container to pass thereunder. Therefore each container will pass under and support the carriage, and the downward movement of the carriage will be limited by the height of the container.

The carriage is raised and lowered for each container and this raising and lowering is accomplished by means of a bell crank cam lever 86 pivoted on the frame at 87. The front end

of one arm of the lever is provided with a link 88 which is pivotally secured to and normally supports the carriage 63. The other arm of the bell crank lever 88 is provided with a cam roller 89 which engages a cam 90 secured to the shaft 73 and rotatable therewith. This cam 90 is so designed that the movement of the carriage is synchronized with the movement of the containers so that the upper front edge will be engaged thereby at the proper time during the downward movement of the carriage. The cam 90 may be adjustably secured to the shaft 73 or a suitable adjustment may be provided by securing the cam to the sprocket 78 by slot and bolt connections in the same manner as for the cam 77.

An adhesive applying mechanism is mounted on the carriage 63 as shown particularly in Figs. 1, 8, and 9 and comprises a transverse shaft 91 mounted in suitable bearings on the carriage and extending laterally on each side thereof. On each end of the transverse shaft 91 is secured a U-shaped glue roll supporting member 92. A transverse shaft 93 is rotatably mounted in the forwardly extending arms of the members 92 and extends through slots 94 in the side walls of the carriage 63. A glue roller 95 is secured to each end of the shaft 93 and between the arms of its corresponding U-shaped supporting member. A glue box 96 is mounted on each member 92 and arranged to deliver adhesive to its corresponding glue roller in the usual manner. It will be apparent therefore that with both adhesive applying devices mounted on the members 92 and these members secured to the oscillatable shaft 91 the glue rollers may be raised and lowered to provide the usual so-called skip gluing for the upper flaps, and that the glue rollers will apply adhesive to the inside of the outturned upper side flaps of the containers.

In order to permit the raising and lowering of the glue rollers to provide skip gluing, the transmission for driving the glue rollers is mounted on a toggle connection comprising a substantially vertical link 97 pivotally mounted on the glue roll shaft 93 and connected at its upper end to a horizontal arm 98 by means of a stub shaft 99. The horizontal arm 98 is pivotally mounted on the transverse driving shaft 81 at the discharge end of the machine (Fig. 6). The transmission for driving the glue rolls comprises a sprocket 100 secured to the glue roll shaft 93 and connected to a sprocket 101 on the stub shaft 99 by means of a sprocket chain 102. The stub shaft 99 is driven by means of another suitable sprocket thereon and a sprocket chain 103 which is in turn driven by means of a sprocket 104 secured to the transverse drive shaft 81.

In order to raise and lower the glue rolls 95 to provide skip gluing, a cam 105 (Fig. 9) is secured to the glue roll shaft 93 and rests on a cam roller 106 suitably mounted on the carriage 63. By this arrangement, it will be apparent that with each rotation of the glue roller shaft 93 the glue rolls will be raised and lowered to provide suitable skip gluing.

A presser bar 107 (Figs. 1, 6 and 7) is positioned at the rear of the carriage 63 and is provided with upwardly extending supporting rods 108 secured thereto and slidably mounted in guides 109 secured to the frame of the machine. Springs 110 normally retain the presser bars in the down position shown and the forward end of the bar is curved upwardly as illustrated so that it will ride over all the containers passing there-

under and retain the end flaps closed until the side flaps are folded thereover.

Flap closing members 111 are provided on each side of the machine (Figs. 6 and 8) for closing the upper side flaps and may comprise curved rods having their forward ends extending through the conveyor guards 5a and pivotally secured thereunder so that their opposite ends may automatically be raised by containers passing thereunder and in accordance with the height of the containers. The outturned flaps of the container will ride up over these bars and be folded to sealing position. The rearward end of the flap closing members 111 are secured to a V-shaped sheet metal presser plate 112 which is in turn secured to a cross bar 113. This cross bar is provided with down turned ends to which are secured cushion members 114 which are arranged to rest on the conveyor guards as shown in Fig. 6. A suitable weight 112a may be mounted on the plate 112 if desired, to provide a suitable pressure on the closed container flaps. As the containers pass under the rearwardly extending ends of the flap holders and the presser plate 112, the folders and the cross bar 113 thereon will be raised accordingly as the containers pass thereunder.

In order to prevent overlapping of the side flaps as they are being closed, a sheet metal disc 115 is rotatably mounted on an arm 116 which latter is in turn pivotally mounted at 117 on the presser plate 112. The arm 116 normally rests on the cross bar 113 thereby supporting the disc 115. A spring 118 is secured to the presser plate 112 and rests on the disc arm 116. The disc 115 is positioned in the median plane of the machine and is arranged to ride over all of the containers so that as the side flaps are folded inwardly, their edges bear against this disc and overlapping of the flaps is prevented.

As the containers pass from the adhesive applying devices to the discharge end of the machine, the lower flaps are also folded by means of curved folder rods 119 (Fig. 1) which may be rigidly secured to any suitable part of the frame. These folder rods operate in the same manner as those previously described. However they are not movable as the bottom of the containers all pass through the machine in the same horizontal plane.

A flap separating disc 120 is pivotally mounted at 121 (Figs. 1 and 6) and in a position to prevent overlapping of the lower flaps in the same manner as the upper disc 115 prevents overlapping of the upper flaps.

The rear end of the container support 37 is also tapered as shown to enable the flaps to be completely folded as the container passes therefrom. Each container, as it moves from the shelf 31, is supported by a plate or table 122 under the presser plate 112, from which it is pushed by a succeeding container to a suitable conveyor or may be removed in any desired manner.

Figs. 12 and 13 are top and side views respectively of a preferred embodiment of container aligning means which may be substituted for the aligning arms 50 whereby all containers irrespective of width will properly be aligned and directed through the machine in the same plane. In this embodiment, two aligning mechanisms are preferably provided, one adjacent each end of the machine and on opposite sides of the gluing mechanism. The aligning mechanisms may be identical and therefore it is thought that a de-

scription of one will be sufficient for purposes of this specification.

Each aligning mechanism comprises a pair of movable frames 123, one of these frames being positioned on each side of the path of the containers as shown in Fig. 12. A plurality of pulleys 124 is mounted on each frame, and a longitudinal V-belt 125 is mounted on the pulleys and arranged to engage the sides of all containers passing between the frames. Idler pulleys 126 may also be provided if required. The frames 123 are pivotally mounted on arms 127 and 128, which latter are secured to vertical oscillatable shafts 129 and 130 respectively. The shafts 129 on opposite sides of the machine are provided at 15 their lower ends with oppositely disposed arms 131, and these arms are connected by an equalizing link 132. Suitable forwardly extending arms are secured to the shafts 129, and these arms are connected together by means of a tension spring 133, the tension of the spring being adjustable by means of a threaded connection 134 with one of the arms. By this construction, the belt-supporting frames 123 are normally resiliently retained in their innermost position, that is, in a 20 position to engage and align the narrowest container within the limits of the machine, and it will be apparent that when wider containers are inserted in the machine they also will be engaged by the movable belts, and the frames will be 25 spread apart in accordance with the width of the container, and all containers will automatically be aligned in the same plane.

Only one embodiment of the invention has been illustrated and described. However, it will 30 be understood that many modifications and changes in detail may be made by those skilled in the art, and it is desired, therefore, that the invention be limited only by the prior art and the scope of the appended claims.

Having thus described this invention, what is desired to be secured by Letters Patent is:

1. In an automatic universal sealer, the combination with means for conveying consecutive containers of different sizes with the flaps on one end of said containers out of alignment, of movable means automatically positionable with respect to each container to apply adhesive to the flaps of the said one end of all of said containers irrespective of misalignment.

2. In a universal sealer, the combination with means for moving consecutive containers of the same or different sizes or dimensions in a substantially straight line path, said containers having the flaps of both ends unsealed, of means oppositely disposed relative to said path and closely adjacent said flaps for applying adhesive to the adjacent flaps, at least one of said adhesive applying means being automatically adjustable relative to containers of different size to apply adhesive to the adjacent flaps thereof irrespective of container size within the limits of said sealer.

3. In an automatic universal sealer, a conveyor for moving containers of different lengths with open flaps and the flaps of different length containers out of alignment, and a movable gluing means automatically controlled by each container to position said gluing means in accordance with the length of the container to apply adhesive to the flaps thereof.

4. A universal sealer comprising a conveyor for moving containers to a gluing means with their ends to be sealed in different planes, a gluing means adjacent the path of said con-

tainers, means to reciprocate said gluing means to and from said path, the movement of said containers and said gluing means being synchronized whereby the movement of said gluing means is limited by the height of each container to be glued.

5. A universal sealer comprising a conveyor for moving containers to a gluing means with their ends to be sealed in different planes, a gluing means adjacent the path of said containers, a reciprocating carriage for said gluing means, the movement of said containers and said carriage being synchronized whereby the top of each container limits the movement of said carriage to position said gluing means for applying adhesive to said container.

6. A universal sealer comprising a conveyor for moving containers to a gluing means with their ends to be sealed in different planes, a carriage supporting said gluing means adjacent the path of said containers, means to reciprocate said carriage to and from said path, the movement of said containers and said carriage being synchronized whereby the movement of said gluing means in one direction is limited by the height of each container to be glued, and means to move said gluing means relative to said carriage during the gluing operation to provide skip gluing.

7. In a universal sealer having means for moving containers in a predetermined path, the combination with a carriage automatically movable from and toward said path and controlled by successive containers in accordance with their respective dimensions, of adhesive applying means on said carriage and arranged to apply adhesive to consecutive containers when said carriage is adjacent said path, and means to move said adhesive applying means relative to 40 said carriage to cause skip gluing.

8. A universal sealer comprising means for moving containers of different heights in a predetermined path with the bottoms of consecutive containers in a fixed horizontal plane, means for opening the top side flaps to horizontal position, a vertically reciprocable carriage positioned above said path and movable to at least as low as the shortest container, the movement of said containers and said carriage being synchronized to cause said carriage during its downward movement to engage the top of each container and be supported thereby as the container passes thereunder, and adhesive applying means on said carriage and arranged to apply adhesive to the flaps of each container while the carriage is supported thereon.

9. A universal sealer comprising a frame, an elongated shelf supported thereon, a pair of oppositely disposed endless conveyors having flights thereon adapted to move containers of different sizes along said shelf, means for directing said containers onto said shelf with the bottom side flaps thereunder and the end flaps closed and resting on said shelf, means for completely opening said bottom side flaps, means for automatically centering said containers on the vertical axial plane of said shelf irrespective of size, means for applying adhesive to said bottom side flaps, means for closing the top end flaps, means for automatically applying adhesive to the top side flaps irrespective of the height of said containers within the limits of said sealer, and means for closing all of said side flaps.

10. In a universal sealer the combination with means for moving open containers of different

sizes in a predetermined path with their bottoms in the same horizontal plane and their vertical axes all in the same plane, of a carriage positioned above said path, means to close the rear end flap, means to lower said carriage in front of the advancing front end flaps of each consecutive container, the front end of said carriage being formed to close the forward end flap, and to cause said carriage to ride on said container while the container is passing thereunder, means to completely open the top side flaps and means on said carriage to apply adhesive to the inside of said side flaps.

11. In an automatic universal sealer, the combination with means for conveying consecutive containers of different heights in a fixed path, of a vertically movable sealing unit positioned above said path and automatically positionable in response to movement of each container thereunder to apply adhesive to the outturned flaps of said container, means on said unit for folding the upper side flaps outwardly, means on said unit for folding the end flaps inwardly, and means independent of said unit for retaining said end flaps closed and closing said side flaps during continued movement of said containers.

12. In an automatic universal sealer, the combination with means for conveying containers in a fixed horizontal path, said containers being of any dimension between opposite flap groups within the limits of said sealer and in random consecutive order with respect to said dimensions, of automatically positionable gluing means limited in positioning movement by each container in accordance with the respective container dimension for consecutively applying adhesive to the flaps of all of said containers.

13. In an automatic carton sealer, the combination with a movable gluing mechanism for applying adhesive to the tops of consecutively moving cartons, a fixed track, and means for advancing cartons of different sizes along said track in random consecutive order past said gluing mechanism, of means synchronized with said carton advancing means and controlled by each carton for bodily repositioning said gluing mechanism between consecutive adhesive applying intervals to enable application of adhesive to each consecutive container irrespective of size.

14. An automatic machine for applying adhesive to both ends of cartons, comprising a fixed track, a pair of gluing mechanisms in opposed relation with respect to said track, means for advancing cartons of different lengths in random consecutive order along said track and between said gluing mechanisms, and means for bodily repositioning at least one of said mechanisms

with respect to said track between consecutive gluing intervals to enable the application of adhesive to each end of consecutive cartons, said means being controlled by each carton irrespective of size to reposition said mechanism in operative gluing relation thereto.

15. In an automatic universal sealer having a fixed track and means for moving cartons of various heights along said track in random consecutive order and with the upper side flaps open, a gluing mechanism above said track and having glue applicators continuously operable to apply adhesive to the open flaps of all containers passing thereunder, means controlled by the respective successive cartons to bodily reposition said gluing mechanism and applicators relative to the respective height of each carton, and automatic means to intermittently move said applicators to nongluing position with respect to each carton to provide skip-gluing.

16. In a universal sealer the combination with means for moving consecutive containers of the same or different heights or dimensions between the ends to be sealed, in a substantially fixed straight line path, said containers having both ends unsealed and at least some of the flaps open, of means for substantially simultaneously sealing both ends of all of said containers irrespective of varying sizes, said means comprising a pair of glue applicators oppositely disposed with respect to said path, and means controlled by each container for spacing said applicators in accordance with the dimension of the respective container.

17. A structure according to claim 1 characterized by said movable means comprising glue rolls and means for directing said flaps into intimate contact with said glue rolls.

18. A structure according to claim 1 characterized by said movable means including glue rolls and elements for positively urging said flaps into intimate contact with said glue rolls.

19. A structure according to claim 1 characterized by said movable means including glue rolls and elements for positively urging said flaps into intimate contact with said glue rolls, the latter including an upturned lip contactible with the flap to cause the latter to be urged into said intimate contact.

20. A structure according to claim 5 characterized by said movable means comprising glue rolls and means for directing said flaps into intimate contact with said glue rolls, and means for moving said glue rolls relative to said directed flaps to cause skip gluing.

JOHN L. FERGUSON.

CERTIFICATE OF CORRECTION.

Patent No. 2,244,873.

June 10, 1941.

JOHN L. FERGUSON.

It is hereby certified that error appears in the printed specification of the above numbered patent requiring correction as follows: Page 2, first column, line 39, for "andr" read --and--; page 6, second column, line 50, claim 20, for the claim reference numeral "5" read --1--; and that the said Letters Patent should be read with this correction therein that the same may conform to the record of the case in the Patent Office.

Signed and sealed this 26th day of August, A. D. 1941.

(Seal)

Henry Van Arsdale,
Acting Commissioner of Patents.
